Watson E. Coleman, Attorney

UNITED STATES PATENT OFFICE.

ELMER L. SLOAN, OF JOPLIN, MISSOURI.

STEERING-GEAR ANTIRATTLER.

Application filed September 16, 1921. Serial No. 501,150.

To all whom it may concern:

Be it known that I, ELMER L. SLOAN, a citizen of the United States, residing at #626½ Main Street, in Joplin, in the 5 county of Jasper and State of Missouri, have invented certain new and useful Improvements in Steering-Gear Antirattlers, of which the following is a specification, reference being had to the accompanying 10 drawings.

This invention relates to attachments for motor vehicles and has for its object the provision of a spring device adapted to be engaged upon the steering spindle arm and 15 also engaged with the associated end of the steering arm connecting rod for the purpose of preventing rattling of these parts when the usual bushings become worn and permit play.

20 An important object is the provision of a device of this character which is formed from a single length of spring wire and which is so constructed that it may be properly engaged with the parts to be prevented 25 from rattling without any necessity for the employment of tools and without requiring any alterations whatever in the existing structure.

An additional object is the provision of 30 a device of this character which will be very simple and inexpensive in manufacture, easy to apply, efficient in action, durable in service and a general improvement in the art.

35 With the above and other objects and advantages in view, the invention consists in the details of construction to be hereinafter more fully described and claimed, and illustrated in the accompanying drawings, in 40 which:

Figure 1 is a perspective view of my device associated with a steering spindle arm and connecting rod; and

45 Figure 2 is perspective view of my device alone.

Referring more particularly to the drawings, the letter A designates a steering arm which extends from the ordinary spindle body which is pivoted at the ends of the 50 front axle of an automobile, and B designates the forked yoke which is carried by each end of the rod C which connects the arms A. This connection is effected by means of a spindle bolt D which passes 55 through the bushing which is generally associated with the steering arm. After any

extended use such bushings invariably become greatly worn and permit a considerable play which naturally results in a very 60 objectionable rattling.

In order to overcome this objection I make use of a tension device which comprises a spring member which is formed from a single length of wire 10 which is bent or coiled partly upon itself, as shown 65 at 11, to define a relatively long arm 12. From the coil 11 the wire is bent to extend at an angle to define an inclined arm 13 which has its intermediate portion bent at 14 to define a second inclined arm 15 which 70 extends at substantially right angles to the arm 14, and the free end of the arm 15 is bent upon itself, as shown at 16, to define a hook 17.

In applying the device the arm 12 is inserted through the fork of the yoke B and the hook 17 is engaged upon the steering arm A with the inclined arm 15 extending across the top of the steering arm, with the arm 13 extending across the bottom of the 80 steering arm and with the coil 11 disposed against the inner edge of the steering arm. When the device is thus applied it will be apparent that the hook 17 cannot become disengaged accidentally from the steering 85 arm and that the arm 12 cannot slip out of the fork in the yoke. The arm 12 of course exerts a strong downward pressure against the upper side of the lower portion of the yoke and will naturally result in preventing 90 rattling will be positively prevented.

From the foregoing description and a 95 study of the drawings it will be apparent that I have thus provided a very simple spring tension device which will efficiently operate to hold the steering rod of an automobile associated with the steering spindle arms so as to prevent play, the device being naturally constructed in rights and lefts for use at different sides of the vehicle or at different ends of the connecting rod. It is also to be noted that the device 100 may be applied merely by the fingers, no tools being necessary for either placing the device in position or removing it in case such should be desired for any reason.

While I have shown and described the 110 preferred embodiment of the invention, it is of course to be readily understood that

I reserve the right to make such changes in the form, construction and arrangement of parts as will not depart from the spirit of the invention or the scope of the subjoined claims.

Having thus described my invention, I claim:

1. Means for preventing rattling at the point of connection of the steering spindle arm with the steering arm connecting rod yoke of a motor vehicle comprising a spring member formed from a single length of resilient wire coiled intermediate its ends to define a relatively long arm engageable against the upper side of the lower portion of the connecting rod yoke, said coil being disposed against one edge of the steering spindle arm, said wire member being bent to define an arm extending from said coil diagonally across the under side of the steering arm and further bent to define a second
- 10
- 15
- 20

inclined arm extending diagonally across the top of the steering arm and terminating in a hook engaging upon the edge thereof.

2. Means for preventing rattling at the point of connection of the steering spindle arm with the steering arm connecting rod yoke of a motor vehicle comprising a spring member formed from a single length of resilient wire bent intermediate its ends to define an arm engageable against the connecting rod yoke and disposed against one edge of the steering spindle arm, said wire member being further bent to define angularly disposed arms one of which extends from said coil, and which arms engage opposite sides of the steering arm, the other of said arm terminating in a hook engaging upon the edge of the steering arm.

In testimony whereof I hereunto affix my signature.

ELMER L. SLOAN.
